UNITED STATES PATENT OFFICE

2,294,012

ROTARY ENGINE

Heinrich Franz Vosseler and Harry Albert William Pierard, Stratford, New Zealand, assignors to said Vosseler, said Pierard, and William Henry Young, Hawera, New Zealand, and Bertram George Aiken Harkness, New Plymouth, New Zealand

Application November 13, 1939, Serial No. 304,251
In New Zealand November 18, 1938

1 Claim. (Cl. 121—71)

The invention relates to rotary engines of the type wherein a rotor is provided with projections from its periphery, made to extend into and fit an annular chamber or cylinder in a stator and in which said projections travel, and also wherein working fluid is introduced into said annular chamber or cylinder behind the aforesaid projections and in advance of means for closing the passage or cylinder, inlet and exhaust ports being provided to and from, respectively, said annular chamber or cylinder, at opposite sides of the annular chamber or cylinder closing means.

The rotary engine provided by the invention comprises a stator having a rotor mounted therein to provide an annular chamber between said rotor and said stator; cross ribs on the periphery of the rotor; rotary closures operating in the stator and said chamber, and containing cross recesses adapted to receive the cross ribs of the rotor; and inlet and outlet ports in said stator in communication with said annular chamber.

In the accompanying drawings, in conjunction with which the invention will be more particularly described,

Figure 1 is a part elevation and part sectional elevation of the improved engine, and

Figure 2 is a plan view of same, while

Figure 3 is a sectional view of the engine taken on the line 3—3, Figure 1, and

Figure 4 a part cross sectional view taken through one of the ports.

The rotor 1 and the stator 2 are formed, and the former is mounted within the latter, so that an annular chamber or cylinder 3 is provided between the periphery of the rotor 1 and the stator 2, the cross sectional shape of said annular chamber or cylinder 3 being of any suitable form, which can conveniently be rectangular.

The periphery of the rotor 1 has thereon a number of cross ribs or projections 4, spaced equidistantly around the rotor 1 and which extend into and are a working fit in the annular chamber or cylinder 3, so as to be capable of travelling in a circular direction through same.

At predetermined points in the annular chamber or cylinder 3 the latter is closed by circular rotary closures 5 which project into the chamber or cylinder 3 from the stator 2, said closures 5 containing in their peripheries cross recesses or grooves 6, designed to receive and accommodate the cross ribs or projections 4 on the rotor 1 for the purpose of permitting said cross ribs or projections 4 to pass the closures 5, the latter and the rotor 1 being geared together as at 7 (Figure 55

3) and the gear ratio being arranged so that the recesses or grooves 6 are presented to the ribs or projections 4 as required to accommodate same.

Inlet and exhaust ports 8 and 9 respectively in the stator 2 communicate with the annular chamber or cylinder 3 adjacent each rotary closure 5, there being an inlet port 8 and an exhaust port 9 at opposite sides of each of said rotary closures 5.

10 A connecting passage 10 in one wall of the stator 2 connects the ports 8 with each other so that the latter are enabled to be supplied with working fluid from a single inlet 11, also the ports 9 are connected with each other by a passage 12 in the opposite wall of the stator 2 so as to exhaust through a common outlet 13.

Working fluid introduced into the annular chamber or cylinder 3 via the inlet ports 8 acts on the cross ribs or projections 4 in advance of 20 the inlet ports 8, according to the direction of rotation of the rotor 1, and imparts turning movement to the latter, while expended fluid in advance of the cross ribs or projections 4 is exhausted via the exhaust ports 9, as said cross ribs 25 or projections 4 travel towards same.

The cross ribs or projections 4 are spaced around the rotor 1 to avoid a dead centre effect, and as each rib or projection 4 passes a rotary closure 5 a charge of working fluid is received 30 in the annular chamber or cylinder 3 between the rib or projection 4 and the closure 5 to give an impulse to the rotor 1, the number of impulses imparted thereto per revolution being equal to the number of cross ribs or projections 35 4 multiplied by the number of inlet ports.

Sealing rings, bearings, lubricating and cooling means are provided in accordance with known practice.

The direction of rotation of the rotor 1 can 40 be changed by reversing the inlet and the exhaust ports, also the engine can be driven and utilised as a suction and delivery pump.

Attention is directed to the fact the present motor is particularly adapted to be mounted in 45 a suspended position and with this point in mind the stator includes a body the upper portion of which is shaped to form annular and flanged attaching sections 14 such sections having the inlets and outlets 11 and 13 extended therethrough. 50 The lower portion 15 acts as a spacing means for the pairs of side plates 16 and 17 which are clamped thereto in juxtaposed relation by nut and bolt arrangements 18. In the central portion of the body member the annular chamber 3 and the secondary chambers for housing the

rotary closures 5 are provided, as indicated. Incidentally the ports 8 and 9 are provided in the inner plates 16 while the passages or chambers 10 and 12 are provided in and between the adjacent contacting faces of the plates 16 and 17. The rotor shaft 19 is mounted in bearings 20 seated in openings in the inner plates 16 and recesses in the outer plates 17 while the outer faces of the latter plates are fitted with packing devices 21 about the shaft 19.

What we do claim and desire to obtain by Letters Patent of the United States of America is:

A rotary engine comprising a stator, including a body portion having a central chamber provided therein and also having secondary chambers communicating with the main chamber and further having a main inlet and a main outlet and pairs of side plates arranged on opposite sides of the body portion and in juxtaposed relation with each other, a rotor positioned in the main chamber and having its shaft journaled in the side plates, cross ribs on the periphery of the rotor, rotary closures arranged in the secondary chambers and having cross re-

cesses adapted to receive the cross ribs of the rotor, inlet and outlet ports provided in the body portion and in the side plates and in communication with the main inlet and main outlet and corresponding in number to the rotary closures with one inlet port and one exhaust port arranged at opposite sides of each of said closures, a connecting passage provided in and between the juxtaposed plates on one side of the stator 10 for connecting the inlet ports to each other and to the main inlet, and another connecting passage provided in and between the juxtaposed plates on the other side of the stator connecting the outlet ports to each other and to the main outlet whereby a simultaneous feeding and discharging of fluid into and out of the chamber is obtained and the upper portion of the body being provided with annular flanged attaching sections through which are extended the main inlet and the main outlet and by which the entire engine may be mounted in a suspended position.

HEINRICH FRANZ VOSSELER.

HARRY ALBERT WILLIAM PIERARD.
